UNITED STATES PATENT OFFICE.

JUSTUS J. WOLLENHAUPT, OF CINCINNATI, OHIO, ASSIGNOR TO THE MONITOR STOVE COMPANY, OF CINCINNATI, OHIO, A CORPORATION OF OHIO.

PIPELESS HOT-AIR FURNACE FOR BUILDINGS.

1,377,539.

Specification of Letters Patent.

Patented May 10, 1921.

Application filed June 25, 1917. Serial No. 176,692.

To all whom it may concern:

Be it known that I, JUSTUS J. WOLLENHAUPT, a citizen of the United States, and residing at Cincinnati, in the county of 5 Hamilton and State of Ohio, have invented a new and use Improvement in Pipeless Hot-Air Furnaces for Buildings, of which the following specification is a full disclosure.

My invention relates to an improvement 10 in a pipeless hot-air heating furnace for buildings.

An object of the invention is to provide a construction of pipeless furnace adapted for circulating hot air through a main or 15 predetermined portion of a building, and for directing a portion of hot air to a specific room or portion of the building, as a bath-room or bed-room.

Another object is to so correlate the general circulating air provision and the special 20 heating provision, that the latter will not in any material degree take space from the general heating space, or interfere with the circulation arrangement of the several 25 jackets.

The features are more fully set forth in combination with the description of the accompanying drawings, forming a part of this specification, wherein:—

30 Figure 1 is a central vertical section through the furnace.

Fig. 2 is a top plan view.

The furnace body unit forms the fire-box 1, combustion chamber 2 and uppermost 35 radiator 3, of annular construction, surrounding the reduced or conical-like upper end 4 of combustion chamber 2, providing a hot-air circulating space 5, between the combustion chamber outer walls and the inner 40 walls of said radiator. The products of combustion escape into said radiator through passage 6, circulate around the radiator and out through flue 7. Surrounding this body unit is an inner casing 8, having a conical 45 top above the body unit. A second casing 9 surrounds the first, also having a coincident tapered upper end, and reduced diameter throat 10, a third shell 11 surrounds casing 9, also having a conical portion 12 and reduced throat portion 13. These three casings 50 are relatively spaced to form outer, cold-air down chute 14 and the upward, hot-air chute 15, the inner casings terminating above the floor to take in air from the bottom of chute 55 14 and pass it upwardly between casings 8,

9, and between the body and casing 8. 16 represents the inner hot-air chamber containing the heater. A single register 17 covers the concentric throats 10, 13, the cold air going down through the marginal portion and the heated air rising through the interior central portion of said register.

While this construction adequately heats the general run of dwellings and buildings, it sometimes happens that some unusual condition of building or room arrangement renders difficult the heating of some particular room or portion of the building.

It will be seen that any special or auxiliary heating provision which would disarrange the relative spacing and arrangements of the air casings or interfere with the standard structures and installations, would be undesirable, as well as an impairment of the primary heating system efficiency.

To provide this special hot-air supply without interference with or material subtraction from the standard structure, I have conceived of the idea of utilizing the space immediately above the radiator, to 80 take that portion of the heated air passing between the outer, upper wall of the combustion chamber, and the inner walls of the radiator, which will not take from the air current passing upwardly around the outer 85 walls of the radiator.

Accordingly, I provide a hood or cone shell 18, capping the central opening formed by the annular radiator, to catch this interior hot-air current and deliver it as desired through hot-air conduit 19, which leads upwardly and outwardly, and is extended through the taper portions of the three casings.

Having described my invention, I claim:

1. In a hot-air furnace, the combination of a heater having an annular radiator head, said radiator head provided with a vertical hot-air passage centrally therethrough, a plurality of casings surrounding said heater within one another and spaced from each other, providing an outer cold-air down-passage and hot-air up-passage communicating with said outer passage at the lower portion of the heater, a conical shell resting upon the top of said radiator head within the radiator diameter as a cover for said vertical air passage through the radiator and forming a hot-air dome over the heater within the inner upward hot-air passage,

- and a conductor pipe extending through said casings communicating with said dome for a direct heat distributing branch line leading from said heater.
- 5 2. In a hot-air furnace, the combination of a heater having a radiator head, said radiator head intermediately provided with a vertical hot-air passage therethrough, a casing surrounding said heater providing a 10 vertical hot-air chamber around the heater, a conical shell supported upon said radiator head within the radiator diameter as a cover for said vertical hot-air passage and forming

a hot-air dome within said hot-air chamber non-communicative therewith above the 15 radiator head, and a conductor pipe extending through said casing and air chamber communicating with said hot-air dome.

In witness whereof, I hereunto subscribe my name, as attested by the two subscribing 20 witnesses.

JUSTUS J. WOLLENHAUPT.
